UNITED STATES PATENT OFFICE.

THOMAS LA MAIDA, OF NEW YORK, N. Y.

JOCK STRAP.

Application filed April 15, 1921. Serial No. 461,546.

To all whom it may concern:

Be it known that I, THOMAS LA MAIDA, a citizen of the United States, and a resident of New York, borough of Bronx, in the 5 county of Bronx and State of New York, have invented certain new and useful Improvements in a Jock Strap, of which the following is a full, clear, and exact specification.

10 This invention relates to a class of devices adapted to be worn by men.

My invention has for its object primarily to provide a device or jock strap designed to be employed by men for supporting parts in 15 their normal position to prevent undue strain thereof especially when the wearer is undergoing physical exercise, and which is of a form whereby the necessity for removal of the device is obviated, in order to 20 obtain access to the parts as well as being of a form that will not tend to wrinkle or crumple in the crease at the back of the wearer. The invention also contemplates the making of a jock strap of flexible ma-

25 terial, such as cloth, which is free from rubber or the like so that it may be kept in a clean sanitary condition by washing. The invention consists essentially of a pocket element for receiving the parts of the wearer,

30 and extending from part of the edge of the pocket element is a flap member adapted to be detachably fastened to the front part of a belt when worn on the waist. Projecting from the edge of the pocket element ad- 35 jacent to the flap member is a tab member also adapted to be detachably fastened to the belt so that it may be separated from the belt to provide access to the pocket without detaching the flap from the belt. On

40 the pocket element opposite to the flap and tab members is a band having in its central part a pocket, and the free end part of the band is adapted to be detachably fastened to the back of the belt, while in the pocket 45 of the band is a removable flexible stay to prevent tendency of the band to wrinkle or crumple in the back crease of the wearer.

A further object of the invention is to pro- 50 vide a jock strap of a simple, efficient and durable construction which may be made in any suitable size and shape.

With these and other objects in view, the invention will be hereinafter more fully described with reference to the accompanying 55 drawing forming a part of this specification in which similar characters of reference in-

dicate corresponding parts in all the views, and will then be pointed out in the claims at the end of the description.

In the drawing, Figure 1 is a fragmentary view showing a side view of the jock strap embodying my invention applied to a person.

Fig. 2 is an enlarged perspective view showing the front of the band adapted to 65 be used in conjunction with the jock strap.

Fig. 3 is an enlarged perspective view showing the front of the band.

Fig. 4 is an enlarged front elevation of the jock strap.

Fig. 5 is an enlarged rear elevation of the device.

Fig. 6 is a sectional view taken on the line 6—6 of Fig. 5.

Fig. 7 is an enlarged plan of a form of 75 the stay adapted to be used in the device, and

Fig. 8 is a section taken on the line 8—8 of Fig. 7.

The device or jock strap has a pocket ele- 80 ment 10 which may be elliptic or other appropriate shape as well as being of a suitable size, and extending from part of the edge of the pocket element is a flap member, as 11, which is of a form preferably ter- 85 minating with an angular free end, as 12. Also extending from part of the edge of the pocket element 10 adjacent to the flap member 11 is a tab member 13. This tab member may be of a shape having a tapered 90 free end, as 14, and the free end portions of the flap member and tab member may be disposed in somewhat the fashion of a Y relative to the pocket element.

On the edge of the pocket element 10 op- 95 posite to the flap member and tab member is attached one end of a band 15 which is disposed in a direction opposite to the flap and tab members. The pocket element 10, flap member 11, tab member 13 and band 15 100 are preferably made of washable cloth without the use of elastic webbing or rubber parts, in order that the device may be readily cleaned without being damaged by water so that it may be kept in a sanitary condition. 105 The pocket element, flap member, tab mem- 110 ber and band are of combined lengths so that when applied to a person such as a male, as 16, the parts of the wearer may be positioned in the pocket element 10 with the flap member 11 and tab member 13 extending approximately to the front of the waist

of the wearer, while the band 15 extends to the back of the waist of the wearer. In conjunction with the device I may provide a separate belt, as 17, of a suitable type, 5 though the form of the belt shown may be made of canvas or elastic webbing adapted to removably fit closely on the waist of the wearer. On the back of the belt may be provided a depending strap, as 18, having 10 one or a number of spaced buttons, as 19, to which the band 15 is removably attached by providing in the free end of the band a like number of spaced holes, as 20, to allow the band to be buttoned to the belt 17. On the 15 lower edge of the front of the belt 17 may be also a number of spaced buttons, as 21 and 22, and in the free end of the flap member 11 may be spaced holes, as 23, to allow the flap member to be detachably fastened 20 to the belt by being buttoned to the buttons 21, while in the tab member 13 may be a single hole, as 24, to permit the tab member 25 to be buttoned to the button 22 of the belt. The tab member 13 may thus be detached from the belt 17 independently of the flap member 11 to permit access to be obtained to the pocket element 10 when the belt is worn by a person, though obviously the flap member may also be detached from 30 the belt, as occasion requires.

In one of the faces centrally of the band 15 of the device is a pocket 25 which extends lengthwise of the band and the entrance 26 to this pocket is in opposed relation to the free end of the band. In the band at its entrance 26 may be a recess 27 communicating with the pocket 25, and in this pocket is removably inserted a stay, as 28, Figs. 5, 6, 7, 8. This stay may be made 35 of a thin sheet of celluloid, hard rubber or other suitable material which is suitably flexible while being sufficiently stiff to prevent the belt from wrinkling or crumpling at the pocket which when worn is positioned 40 over the back crease of the wearer. The stay is of a size so that one of its ends may be inserted, as shown in Figs. 5 and 6, in the recess 27 to prevent the stay from accidental displacement when arranged in the pocket 45 25, and if desired the stay may be perforated, as at 29, with two of its edges being covered with bindings, as 30 and 31, of flannel or other cloth or the like to prevent the stay from tendency to slip back and forth 50 in the pocket as well as serving to prevent the stay from cracking when the wearer of the device is undergoing physical exercise.

In the foregoing description, I have embodied the preferred form of my invention,

but I do not wish to be understood as limiting myself thereto, as I am aware that modifications may be made therein without departing from the principle or sacrificing any of the advantages of this invention, therefore, I reserve to myself the right to make 65 such changes as fairly fall within the scope thereof.

Having thus described my invention, I claim as new and desire to secure by Letters Patent:—

1. A jock strap, comprising a pocket element having, extending from part of its edge an approximately Y shaped flap member and tab member, both being adapted to be detachably fastened to a belt, a band protruding from a portion of the pocket opposite to the flap and tab members for being removably attached to the back of the belt and the band having in its central part a pocket, and a removable perforated flexible 80 stay in the pocket of the band to prevent the band from wrinkling.

2. A jock strap, comprising a pocket element having extending from part of its edge a flap member adapted to be detachably fastened to a belt, a tab member also protruding from the pocket element adjacent to the flap member, said tab member being adapted to be detachably fastened to the belt, a band protruding from a portion of the pocket opposite to the flap and tab members for being removably attached to the back of the belt and the band having in its central part a pocket, and a removable perforated flexible stay in the pocket of the 95 band to prevent the band from wrinkling.

3. A jock strap, comprising a pocket element having extending from part of its edge a flap member adapted to be detachably fastened to a belt, a tab member also protruding from the pocket element adjacent to the flap member, said tab member being adapted to be detachably fastened to the belt, a band protruding from a portion of the pocket opposite to the flap and tab members 100 for being removably attached to the back of the belt and the band having in its central part a pocket, a removable perforated flexible stay in the pocket of the band to prevent the band from wrinkling, and a 110 belt to which the flap member, tab member and band are detachably fastened.

This specification signed and witnessed this 14 day of April A. D. 1921.

THOMAS LA MAIDA.
